UNITED STATES PATENT OFFICE.

MERVIN V. ARNOLD, OF EVANSVILLE, INDIANA.

EXPANSION VALVE FOR REFRIGERATING MACHINES.

Application filed January 11, 1924. Serial No. 685,580.

To all whom it may concern:

Be it known that I, MERVIN V. ARNOLD, a citizen of the United States, residing at Evansville, in the county of Vanderburgh and the State of Indiana, have invented certain new and useful Improvements in Expansion Valves for Refrigerating Machines, of which the following is a full, clear, and exact description, such as will enable any one skilled in the art to make and use the same.

My invention relates to an improved form of expansion valve particularly designed to be used in connection with a refrigerating apparatus of the compression type in which there is employed the usual compressor, condenser and expansion chamber; the said valve being particularly adapted for use in refrigerating systems of this character employing a refrigerant which boils at atmospheric pressure at a sufficiently low degree below the freezing point to produce the temperature required in a refrigerant at atmospheric pressure.

It is a primary object of this invention to construct a valve in which the difference in pressures of the compression and exhaust sides of the device will be utilized.

It is a further object of this invention not only to seal the compression side, but also to seal the exhaust side of the valve against any pressure leakage.

It is a further object to provide means of adjusting the pressure so that a proper balance may be arrived at and generally to provide improvements in the details of the device.

Other objects will be more fully herein-after set out in the drawings, specifications and claims in which the methods of accomplishing these objects will be more fully herein-after set out.

In the drawings:

Fig. 1, is a sectional elevation on the center line showing fully all the details of the valve.

Fig. 2, is a diagrammatic view on a reduced scale showing the location of the valve and the relation of same to the various parts of a refrigerating system.

Referring now to the drawings in which the various parts are indicated by the same numerals in all the views. 1 is a diagrammatic view of a compressor assembly. 2 is a pressure pipe leading from the compression side of the compressor 1 to a con-

densing coil 3. 4 is a pipe leading from the condensing coil to the lower half 5 of the expansion valve. 6 is a pipe leading from the expansion valve to the expansion coil 7. 60 8 is a suction pipe leading from the expansion coil to the suction side of the compressor 1. 9 is a connecting pipe from the suction pipe 8 to the upper half 10 of the expansion valve.

From this description it will be seen that when the compressor is in operation the compression side will be directly connected to the lower half 5 of the expansion valve and the suction side of the compressor will 70 be directly connected to the upper half 10 of the same expansion valve.

Referring now especially to Fig. 1, the expansion valve consists of an upper or suction half 10 and a lower or compression 75 half 5 separated by a diaphragm 11 which diaphragm is clamped between the flanges 12 and 13 of the lower and upper half respectively and is hermetically sealed by means of gaskets 14 and 15 which gaskets 80 are compressed against the diaphragm by the bolts 16 which hold the two halves of the valve together. The diaphragm 11 is provided with a centrally disposed opening through which the central threaded portion 85 of the flanged member 17 projects, the diaphragm being similarly clamped against the flanges 18 of this member by means of a nut 19. Should it be found necessary, gaskets may be introduced between the 90 flange 18 and the diaphragm 11 to insure hermetical sealing of the joint. 191 is an extremely thin metal bellows which is brazed at its opposite end to an annular plate 20 which plate is adapted to be clamped against 95 the annular shoulder 21 formed in the boss 22 which extends outward from and is integral with the upper half 10 of the valve, the said annular plate being securely clamped against the shoulder 21 by means 100 of the threaded plug 23. This plug 23 is tapped to receive a threaded thumb bolt 24 and is drilled or bored out to slidably receive a cylindrical plug 25, against the upper side of which the thumb bolt 24 bears, and 105 between the lower side of which and the upper side of the flange 18 is a compression spring 26.

While I have not shown it, it will of course be understood that a gasket may be 110 placed between the annular plate 20 and the shoulder 21 in order to secure a hermetically

sealed joint, though I prefer in such case to use white lead, or some such material for this purpose.

27 is a valve stem which is screwed into the flange member 17 and is moved upward and downward by the diaphragm 11. The needle point 28 of this stem co-acts with a seat 29 in the boss 30 extending below the lower half of the valve casing 5. When 10 the balance of pressure between the vacuum in the upper half 10 of the valve, and the pressure in the lower half 5 of the same reaches the determined point as determined by the regulation of the compression spring 15 26, this needle valve opens and permits the compressed refrigerating liquid to flow through the pipe 6 to the expansion chamber. When the pressure builds up in the expansion chamber from the expansion of this liquid 20 to a point above that which the surrounding medium can absorb, the vacuum necessarily becomes less and the valve closes, thus cutting off the flow until the vacuum is again increased.

23 It will be seen from this description that there are a number of points especially stressed so far as the mechanical construction is concerned;

First, the hermetical sealing of the diaphragm 11 between the two halves of the 30 casing.

Second, the sealing of the central opening through the diaphragm, and

Third, the sealing of the upper half of 35 the valve from the adjusting means and from the outside atmosphere at the opening through which this adjusting means is inserted.

It will further be seen that so far as the 40 action of the valve is concerned, that it is governed by three things acting together;

First, the pressure of the refrigerating medium as delivered through the pipe 4.

Second, the vacuum in the upper half of 45 the valve, and

Third, the tension on the compression spring 26.

In this lies the essential difference between my valve and those valves which depend upon the balance of forces between 50 atmospheric pressure and the pressure on the compression side of the refrigerating system. In compression systems of this type the compression pressure if properly regulated, is constant so that it is necessary to introduce some variable which in this case, is the amount of vacuum.

As I have discovered and believe, the balance of the forces between the compression 60 side and the exhaust side of the circulating system is a much better regulator than the balance of the forces between the compression and the atmosphere only.

In order that the invention may be understood, the details of the preferred form

of my device have been set forth but it will be apparent that persons skilled in the art may resort to various modifications without departing from the purpose and spirit of my invention.

Having now fully described my invention what I claim and desire to secure by Letters Patent of the United States is:—

1. In a device of the character described a valve chamber comprising a pressure section, a passage leading from the compression side of a refrigerating system thereto, a centrally disposed boss extending from the said section, a pipe leading from the said boss to the expansion chamber of a refrigerating system; and a vacuum section having a passage leading therefrom to the vacuum side of said system; a diaphragm separating said sections, having its periphery clamped between the peripheral edges of said sections and sealed to each of them, a central opening through said diaphragm, a flanged member having a threaded hub extending through said opening, a nut clamping and sealing said diaphragm to the said member; a valve seat in the boss on the pressure section intermediate said section and said passageway, a valve stem secured into the hub of said flanged member, and having a valve thereon cooperating with said seat, a centrally disposed boss extending from said vacuum section, an outwardly disposed annular seat formed in said boss, an annular plate adapted to seat thereagainst, a cylindrical metal bellows hermetically sealed between said annular flange and said flanged member, a threaded plug securing and sealing said annular plate, a pressure plug, a thumb screw bearing against said plug and a compression spring between said plug and 105 said flanged member.

2. In a device of the character described a valve chamber comprising a pressure section, a passage leading from the compression side of a refrigerating system thereto, a centrally disposed boss extending from the said section, a pipe leading from the said boss to the expansion chamber of a refrigerating system; and a vacuum section having a passage leading therefrom to the vacuum side of said system; a diaphragm separating said sections, having its periphery clamped between the peripheral edges of said sections and sealed to each of them, a central openings through said diaphragm, a flanged member and means passing through said opening clamping and sealing said diaphragm to said member, a valve seat in the boss on the pressure section intermediate said section and said passageway, a valve stem secured into said flanged member, and having a valve thereon cooperating with said seat, a centrally disposed boss extending from said vacuum section, an outwardly disposed annular seat formed in said boss, 115

120

130

- an annular plate adapted to seat there-
against, a cylindrical metal bellows hermeti-
cally sealed between said annular plate and
said flanged member, means securing and
sealing said annular plate, a compression
spring bearing against said flanged member,
and means for regulating the tension thereof.
3. In a device of the character described a
valve chamber comprising a pressure section,
10 a passage leading from the compression side
of a refrigerating system thereto, a pipe
leading from said section, a centrally dis-
posed valve seat between said pipe and said
section, and a vacuum section having a pas-
sage leading therefrom to the vacuum side
of said system; a diaphragm separating
said sections, having its periphery clamped
between the peripheral edges of said sections
and sealed to each of them, a central opening
20 through said diaphragm, a member and
means extending through said opening
clamping and sealing said diaphragm to said
member, a valve stem secured into said mem-
ber, and having a valve thereon cooperating
25 with said seat, a centrally disposed boss ex-
tending from said vacuum section, an out-
wardly disposed annular seat formed in said
boss, an annular plate adapted to seat there-
against, a cylindrical metal bellows hermeti-
cally sealed between said annular plate and
30 said diaphragm member, a threaded plug se-
curing and sealing said annular plate, and
means for regulating the tension against
said diaphragm.
4. In a device of the character described a 35
valve chamber, comprising a pressure sec-
tion, a passage leading from the compression
side of a refrigerating system thereto, a
centrally disposed pipe leading from the
said boss to the expansion chamber of a re-
frigerating system, a valve seat between said
40 pipe and said section, and a vacuum section
having a passage leading therefrom to the
vacuum side of said system; a diaphragm
separating said sections, having its periph-
ery clamped between the peripheral edges
45 of said sections and sealed to each of them, a
central opening through said diaphragm, a
flanged member, means clamping and seal-
ing said diaphragm to said member, a valve 50
stem secured into the said flanged member,
and having a valve thereon co-operating
with said seat, a centrally disposed boss ex-
tending from said vacuum section, an out-
wardly disposed annular seat formed in said 55
boss, an annular plate adapted to seat there-
against, a cylindrical metal bellows hermeti-
cally sealed between said annular flange and
said flanged member, means securing and
sealing said annular plate, and means for 60
regulating the tension against said dia-
phragm.

In testimony whereof I have hereunto set
my name.

MERVIN V. ARNOLD.
